UNITED STATES PATENT OFFICE

168,894

RUG CUSHION OR SIMILAR ARTICLE

Theodore Horwich, Chicago, Ill., assignor to General Felt Products Co., Chicago, Ill., a corporation of Illinois

Application February 6, 1952, Serial No. 18,416

Term of patent 14 years

(Cl. D92—4)

To all whom it may concern:

Be it known that I, Theodore Horwich, a citizen of the United States, residing at Chicago, in the county of Cook and State of Illinois, have invented a new, original, and ornamental Design for a Rug Cushion or Similar Article, of which the following is a specification, reference being had to the accompanying drawings forming a part thereof, in which

Fig. 1 is a fragmentary plan view of the rug cushion or similar article embodying my new design;

Fig. 2 is a fragmentary sectional view taken along line 2—2 of Fig. 1.

I claim:

The ornamental design for a rug cushion or similar article, substantially as shown.

THEODORE HORWICH.
